UNITED STATES PATENT OFFICE

LEONARD F. CLERC, OF DETROIT, MICHIGAN

STREET CAR

Application filed November 19, 1928. Serial No. 320,336.

The present invention pertains to a novel construction in a street car whereby there are provided two separate entrance doors, one for the use of passengers who have paid their fare before boarding the car, and the other for the use of passengers who have not paid their fare.

In many cities there are provided so-called safety zones at the more important car stops, and where a large number of people congregate in these zones, particularly during rush hours, much time can be saved by collecting their fares on their entrance into the zones or at least before they board the street car. On boarding the car they may then pass directly to their seats without being required to pass through the usual restricted gate at which the fare is ordinarily collected.

The object of this invention is to provide a street car construction for use in conjunction with such a system. The main seating compartment has an entrance door which is used by passengers who have paid their fare before boarding the car. For the use of passengers who board the car at irregular or intermediate stops, there is provided another entrance door leading to a vestibule which is partitioned from the main seating compartment. In this partition or barrier is a gate controlled by a turnstile and equipped with a fare box, and the box is preferably connected to the turnstile in such a manner that the latter will automatically be operated on deposit of the fare into the fare box.

The invention is fully disclosed by way of example in the following description and in the accompanying drawing, wherein the single figure illustrates a horizontal section of a street car constructed according to the invention.

The conventional street car structure, including the wall, is indicated in general by the numeral 1, and it will be seen that the greater part of the space within the car constitutes a seating compartment 2 equipped with seats 3 in any desired arrangement. In the wall of the car is provided a door 4 which leads directly to the seating compartment 2.

Across the front end of the car is built a

barrier or partition 5 which forms a vestibule 6. In this barrier is a gate or opening 7 permitting access to the seating compartment 2, but this gate is controlled by a turnstile 8. A guard 9 is provided at the side of the turnstile in order to prevent injury to passengers standing in the seating compartment. The vestibule 6 is entered by a door 10 disposed adjacent the door 4 but at the other side of the partition 5.

In the gate or opening 7 is a fare box 11 which is preferably geared as at 12 to the turnstile 8 in such a manner as to operate the latter when the proper fare is deposited in the box.

In the operation of the car in accordance with the system already outlined, the car is brought to rest in such a position that the door 4 registers with a safety zone or loading station occupied by passengers who have already paid their fare. The motorman opens only the door 4, so that the occupants of the zone may proceed directly to the seats 3.

At irregular or intermediate stops where the passengers do not pay their fare before boarding the car, only the door 10 is opened so that these passengers must pass through the vestibule 6 and gate 7 and must deposit their fare in the fare box 11 in order to be admitted to the seating compartment 2 through the turnstile 8.

In the vestibule 6 is also built a partition or wall 13 which defines the motorman's cab 14. At the rear end of the car is an exit door 15 adjacent which is a floating platform 16 mounted in the floor of the car. This platform operates a switch 17 having one terminal connected to the usual trolley by a conductor 18 and the other terminal connected by a conductor 19 to one terminal of a lamp 20 supported in the cab 14 and within sight of the motorman. The remaining terminal of the lamp 20 is grounded as at 21 whereby a circuit through the switch 17 and the lamp is completed.

A passenger wishing to alight proceeds to the exit door 15 and stands on the platform 16. His weight on the platform causes the switch 17 to close whereby the lamp 20 is lighted, and a signal is thus given to the

100

motorman that at least one passenger is ready to alight. The motorman therefore stops the car at the next car stop and, by mechanism which need not be described here, opens the 5 door 15.

Although a specific embodiment of the invention has been illustrated and described, it will be understood that various alterations in the details of construction may be made 10 without departing from the scope of the invention, as indicated by the appended claim.

What I claim is:—

In a one man street car having a rear exit, a seating compartment, a vestibule at one 15 end thereof, a barrier between said compartment and vestibule, entrance doors in the wall of said car at opposite sides of said barrier and leading respectively to said compartment and vestibule, and a gate in said barrier.

20 In testimony whereof I affix my signature.
LEONARD F. CLERC.
